US00D848054S

(12) **United States Design Patent** (10) **Patent No.:** **US D848,054 S**
Zhan (45) **Date of Patent:** **** May 7, 2019**

(54) **SPOTLIGHT**

(71) Applicant: **Fuzhou F&V Photographic Equipment Co., Ltd.**, Fuzhou (Fujian) (CN)
(72) Inventor: **Qiang Zhan**, Fuzhou (CN)
(73) Assignee: **Fuzhou F&V Photographic Equipment Co., Ltd.**, Fuzhou (Fujian) (CN)

(**) Term: **15 Years**

(21) Appl. No.: **29/566,631**

(22) Filed: **Jun. 1, 2016**

(51) **LOC (11) Cl.** **26-05**

(52) **U.S. Cl.**

USPC **D26/118**

(58) **Field of Classification Search**

USPC ... D26/2, 20, 27, 30, 31, 32, 24, 25, 35, 36, D26/42, 46, 55, 61, 69, 70, 71, 76, 72, D26/85, 113, 78, 80, 88, 89, 101, 110, D26/109, 118-120, 123, 124, 127, 128, D26/130, 133, 134, 138, 139; D11/144; D12/114; D6/302, 309

(57) **CLAIM**

The ornamental design for a spotlight, as shown and described.

DESCRIPTION

FIG. 1 is a perspective view of a spotlight showing my new design;

FIG. 2 is a left side view of the spotlight shown in FIG. 1; FIG. 3 is a right side view of the spotlight shown in FIG. 1; FIG. 4 is a front view of the spotlight shown in FIG. 1; FIG. 5 is a rear view of the spotlight shown in FIG. 1; FIG. 6 is a top view of the spotlight shown in FIG. 1; and, FIG. 7 is a bottom view of the spotlight shown in FIG. 1. The broken lines showing portions of the body, base, handles, and ventilation slots of the spotlight are included to show features that form no part of the claimed design.

1 Claim, 7 Drawing Sheets
